(57) **CLAIM**

The ornamental design for a combined confectionery product package and dispenser, as shown and described.

DESCRIPTION

FIG. 1 is a side perspective view of a combined confectionery product package and dispenser of the new design.

FIGS. 2 and 3 are front and back elevational views, respectively, of the combined confectionery product package and dispenser of FIG. 1.

FIG. 4 is a top plan view of the combined confectionery product package and dispenser of FIG. 1; and,

FIG. 5 is a bottom plan view of the combined confectionery product package and dispenser of FIG. 1.

The broken line portion of the Figures is included to show unclaimed subject matter and forms no part of the claimed design.
